United States Patent Office

Des. 214,502

Patented June 24, 1969

214,502

DENTAL CABINET OR THE LIKE

Arthur L. Jones, Charlotte, N.C., assignor to The Pelton & Crane Company, Charlotte, N.C., a corporation of North Carolina

Filed May 14, 1968, Ser. No. 11,915

Term of patent 14 years

Int. Cl. D6—01; D23—02
U.S. Cl. D24—1

FIG-1

FIG-2

FIG-3

FIG-4

FIGURE 1 is a front perspective view of the dental cabinet showing my new design;

FIGURE 2 is a top plan view thereof;

FIGURE 3 is a left side elevational view thereof; and FIGURE 4 is a right side elevational view thereof.

The back of the cabinet is plain and conventionally flat.

The dominant features of my design reside in those portions shown in full lines.

I claim:

The ornamental design for a dental cabinet or the like, substantially as shown and described.
